UNITED STATES PATENT OFFICE

149,809

DESIGN FOR A MEAT LUG

James M. Gordon, Los Angeles, Calif.

Application December 29, 1945, Serial No. 125,194

Term of patent 14 years

(Cl. D58—4)

To all whom it may concern:

Be it known that I, James M. Gordon, a citizen of the United States and a resident of Los Angeles, California, have invented a new, original, and ornamental Design for a Meat Lug, of which the following is a specification, reference being had to the accompanying drawing, forming part thereof.

Referring to the drawing:

Figure 1 is a perspective view of a meat lug, showing my new design;

Figure 2 is a side elevational view of the device;

Figure 3 is a top plan view thereof; and,

Figure 4 is an end elevation of the device.

I claim:

The ornamental design for a meat lug, as shown.

JAMES M. GORDON.
